UNITED STATES PATENT OFFICE.

THOMAS H. DARDANI, OF BLOOMFIELD, NEW JERSEY.

COMBINATION JACK AND HOIST.

Application filed February 8, 1922. Serial No. 534,919.

To all whom it may concern:

Be it known that I, THOMAS H. DARDANI, a citizen of the United States, residing at Bloomfield, in the county of Essex and State 5 of New Jersey, have invented certain new and useful Improvements in Combination Jacks and Hoists; and I do hereby declare the following to be a full, clear, and exact description of the invention, such as will enable others skilled in the art to which it 10 pertains to make and use the same, reference being had to the accompanying drawings, and to characters of reference marked thereon, which form a part of this specification.

This invention relates, generally, to improvements in combined lifting jacks and hoists; and, the present invention has reference, more particularly, to a novel combination jack and hoist for use especially with automobiles which is simple in its construction and is effective, both for lifting the axle and wheel of a vehicle for a change of tires, or for drawing or pulling the vehicle 25 out of the sand or mire when the wheels have become imbedded in a manner, that the wheels when operated will not grip, and will cause a possible loss, due to battery-exhaustion, strain upon the engine, or wear 30 and tear upon the tires.

The present invention has for its principal objects to provide a novel and simply constructed combination jack and hoist of the general character hereinafter more particularly set forth and for the purposes herein-before stated, which is most simple in its construction, is positive in its action, and is adapted for use either as a jack for lifting purposes, or as a hoist for pulling the 35 vehicle out of a ditch or over an embankment, or out of the sand or mud, when deeply mired therein.

Other objects of the present invention not at this time more particularly enumerated 40 will be clearly understood from the following detailed description of the same.

With the various objects of the invention in view, the said invention consists, primarily, in the novel combination jack and hoist hereinafter more fully set forth; and, the said invention consists, furthermore, in the novel arrangements and combinations 50 of the various devices and parts, as well as in the details of the construction of the said 55 parts, all of which will be more fully described in the following specification, and

then finally embodied in the clauses of the claims, which are appended to and which form an essential part of the said specification.

60

The invention is clearly illustrated in the accompanying drawings, in which:—

Figure 1 is a detail view of the combination jack and hoist shown in a horizontal position with a flexible element extending 65 from each end horizontally to illustrate the use of the device when in tension in connection with a vehicle for pulling the same out of a ditched or mired position.

Figure 2 is a side elevation of a combination jack and hoist, made according to and embodying the principles of the present invention; and Figure 3 is an edge view of the same, looking in the direction of the arrow *x* in said Figure 2.

Figure 4 is a transverse vertical sectional representation of the said device, said section being taken on line 4—4 in said Figure 3, looking in the direction of the arrow *y*; and Figure 5 is a similar sectional representation of the same, said section being taken on line 5—5 in said Figure 3, looking 70 in the same direction.

Figure 6 is a horizontal section, taken on line 6—6 in said Figure 3; and Figure 7 is 75 a detail vertical representation of the parts represented in said Figure 6, said section being taken on line 7—7 in said figure.

Figure 8 is a face view of certain portions of the device, looking in the direction of the 80 arrow *u* in said Figure 7, with a portion of the gear-casing shown broken away; and Figure 9 is a fragmentary view, showing the jack-feature partly in perspective and partly in section.

Figure 10 is a detail horizontal sectional representation taken on line 10—10 in said Figure 8.

Similar characters of reference are employed in all of the said above described 100 views, to indicate corresponding parts.

Referring now to the several figures of the drawings, the reference-character 1 indicates a complete combination jack and hoist, showing one embodiment of the principles of the present invention, the same comprising a main shell or casing consisting of a base-plate 2 formed with suitably disposed openings, as 3. Suitably mounted upon said base-plate 2 are two vertically disposed side-plates 4 and 5, which are preferably slightly contracted toward each other,

85

90

95

100

105

110

- as at 6 and 7, see Figures 6 of the drawings, to provide a narrow space-portion 8 in which is vertically disposed and movably arranged a rack-member 9 formed upon one edge with pawl-engaging teeth 10 and upon its upper end with a supporting or engaging end 11, adapted to be moved against an axle 12 of the vehicle for lifting purposes, as indicated in Figure 4 of the drawings. A 5 spacing-plate 13 and a gate-plate 14 are arranged between said side-plates 4 and 5, the said plate 13 and the side-plates 4 and 5 being secured together by means of tie-bolts or screws 15, and the said gate-plate 14 10 and side-plates 4 and 5 being secured together by means of a tie-bolt or screw 16 which also acts as a means of pivotal connection for the said gate-plate 14, and a tie-bolt or screw 17 with which a hook-shaped portion 141 of the said gate-plate 14 can be brought into separable holding engagement, as will be evident from an inspection of said Figure 4 of the drawings. At the proper locations between the said 15 side-plates 4 and 5 are suitably formed guide-members or elements, as 18 extending inwardly from an opening 20, and a guide-member 19 secured in place by a tie-bolt or screw 21, as shown, for properly 20 maintaining the rack-member 9 in its vertically movable relation between the said side-plates 4 and 5, as will be evident. Extending through a suitably disposed perforation in the guide-member or element 25 35 and through correspondingly placed perforations in the side-plates 4 and 5 is a pin or stem 22 the ends of which project beyond the outer faces of said side-plates for the pivotal arrangement thereon of the eyes 40 45 50 55 60 65 24 of a bail 23 to which may be attached a chain 25, or the like, for the purposes hereinafter more fully set forth. Pivotally mounted upon a pin or stem 26 extending across the space between the said side-plates 4 and 5 is a lever-receiving socket-member 27 preferably of the construction shown in Figures 3 and 4 of the drawings, for the reception of the end-portion of an operating lever or handle 28, which may be detachably secured in said socket-member and maintained in its operative relation with said member by a removable cross-pin 29. Pivotally mounted upon said pin or stem 26 is an upwardly extending dog or pawl 30, the said socket-member 27 being provided with another pin or stem 31 upon which is pivotally mounted a second upwardly extending pawl or dog 32, a suitably formed spring, as 33, connecting the said pawls or dogs 30 and 32, for forcing their rack-engaging end-portions into slidable engagement with the teeth 10 of the rack-member 9, as will be evident. The manner of raising the rack-member 9, by means of said 70 75 80 85 90 95 100 105 110 115 120 125 130 pawls or dogs and the handle or lever 28

will be clearly understood from an inspection of Figure 4 of the drawings, and is as follows:

Let us suppose that the various parts of the device are in the positions indicated in Figure 4 of the drawings, and that the rack 9, with its load 12 is to be raised, the two pawls 30 and 32 being in the position shown. The operator throws the pivoted latch or lever 34 in a direction toward the rack-member 9, causing the lug 35 of said latch or lever 34 to be rotated in a downward direction until its free end-portion is forcibly brought into contact with that portion of the spring 33 where its end-portion is attached to the side of the pawl 30. By lifting the lever 28, the engaging portion of the pawl 30 remains in engagement with the rack 9, the pawl 32 being moved in a downward direction a sufficient distance to permit the spring 33 to act toward and upon said pawl 32, thus forcibly bringing its engaging end in holding engagement with the oppositely disposed tooth of the rack 9, as will be evident. The lever 28 now being swung in a downward direction, the engaging end-portion of the pawl 32 causes the rack 9 to be moved in an upward direction, the pawl 30 being forced out of its engagement with the tooth of the rack, 95 but being immediately forced into active engagement with the next succeeding tooth of the rack 9, by the action of the spring 33, and whereby the rack and its load are maintained in their raised positions, as will be clearly understood. Thus, by the action of the lever back and forth, an alternating step by step engagement of the dogs or pawls 30 and 32 with the rack-teeth may be had, so as to move the rack the desired distance, 100 according to the height that it is intended to lift or raise the load 12 above the ground.

When it is desired to lower the rack step by step, the operator returns the latch or lever 34 to its former position, indicated in said Figure 4 of the drawings, thereby withdrawing the lug 35 from its engagement with the spring 33. A downward movement of the lever 28, owing to the action of the spring, forces the pawl 32 into lifting engagement with the rack, and raises the same slightly, so that the spring 33 now forces the other pawl 30 out of its engagement with the rack, and so that as the lever 28 is raised, the rack, still in engagement with the pawl 32 moves in a downward direction, while the spring 33 acts to force the pawl into active engagement with the succeeding and downwardly moving tooth of the rack, as will be clearly evident.

If desired the rack-member 9 may also be provided in its opposite sides with grooves or channels 37, the opposite portions 6 and 7 of the side-plates 4 and 5 in that case being formed upon their inner faces with corre-

spondingly placed guide-lugs or protuberances, as 38, and as indicated more particularly in Figure 10 of the drawings.

Referring now to Figures 2, 3 and 5, there is attached by means of some of the tie-bolts or screws 15, the tie-bolt or screw 16, and the cross-pin 36, in a proper location upon the outer face of the side-plate 4, a shell or casing 39 across the chamber formed by it and the said side-plate 4, also extends the previously mentioned pin or stem 26. Disposed within the chamber thus formed and mounted upon a shaft 40 is a ratchet-wheel 41, the said shaft 40 being rotatably journaled in a bearing-portion 42 in said shell or casing 39, see Figures 2 and 3, and in correspondingly disposed bearing-portions 43 and 44, indicated in dotted outline in Figure 7 of the drawings. Suitably secured upon the outer face of the side-plate 5, by means of screws 45, see Figure 8, or in any other suitable manner, is a gear-casing 46, in which is disposed a pinion 47, the hub-portion 48 of which is suitably affixed to the end-portion of the shaft 40 which also extends into the chamber formed by said gear-casing 46 and the outer face of the side-plate 5. The said side-plates 4 and 5 are also provided with other bearing-positions, as 49 and 50, in which is journaled a shaft 51, having suitably affixed thereon by means of a set-screw 52, or in any other suitable manner, in the space between said side-plates 4 and 5, a suitably formed chain-carrier or sheave 53 with which can be brought in active engagement the links of a chain 54, the ends of said chain, ordinarily, being movably disposed in the openings 3 of the base-plate 2, substantially as indicated in Figure 4 of the drawings. Rotary motion of said shaft 51 and said chain-carrier or sheave 53 is obtained from a gear-wheel 55 which is suitably fixed upon that end-portion of the shaft 51 which extends into the chamber formed by said gear-casing 46 and the said side-plate 5, said gear-wheel 55 being actuated from the pinion 47 which is in mesh therewith, in the manner and for the purposes to be presently set forth. Pivotaly mounted upon that portion of the previously mentioned pin or stem 26 which extends across the above-mentioned chamber formed by the shell or casing 39 and the side-plate 4 is a lever-receiving socket-member 56, similar in its construction to that of the socket-member 27, said socket-member 56 being adapted to receive the end-portion of the previously mentioned operating lever or handle 28, as indicated in Figure 5 of the drawings, said lever being detachably secured in said socket member 56 by means of a removable cross-pin 57. Also pivotally mounted upon said pin or stem 26 is a downwardly extending pawl or dog 58, the said socket-member 56 being provided with another pin

or stem 59 upon which is pivotally mounted a second downwardly extending pawl or dog 60, a suitably formed spring, as 61, connecting the said pawls or dogs 58 and 60, for forcing their engaging end-portions into 70 slidable and active engagement with the teeth of the ratchet-wheel 41, in substantially the same manner, as previously described in connection with the pawls 30 and 32, and the rack 9. The manner of actuating the chain-carrier or sheave and the chain from the said ratchet-wheel, when operated by the handle or lever 28 and the dogs or pawls 58 and 60 will be clearly understood from an inspection of Figures 5, 6, 7, and 8 of the drawings, and any further description of the same is therefore deemed unnecessary, and from an inspection of Figure 1, one manner of using these last-described elements of the device as a hoisting 80 or pulling means will be clearly understood.

When the device is to be used as a jack, in order that the device may be properly placed upon its base-plate 2, the gate-plate 14 may be moved into its opened position, 90 in which case the strands of chain are withdrawn through the openings 3 in the base-plate 2, and drawn out through the opened portion of the main casing, but without having to remove the chain from the chain-carrier or sheave.

From the foregoing description of the present invention, it will be seen that I have produced a simply constructed and effectively operating device, which is readily convertible into a jack for lifting purposes, or into a hoist adapted for various uses to which a hoist is applicable.

Of course, I am aware that changes may be made in the general arrangements and combinations of the various devices and parts, as well as in the details of the construction of the said parts, without departing from the scope of the present invention as set forth in the foregoing specification, 105 and as defined in the clauses of the claims which are appended thereto. Hence, I do not limit my present invention to the exact arrangements and combinations of the said devices and parts as described in the said specification, nor do I confine myself to the exact details of the construction of the said parts, as illustrated in the accompanying drawings.

I claim:—

1. A combination jack and hoist, comprising a chambered standard, a jack-mechanism and a hoist-mechanism disposed in said standard, a means of pivotal support within said standard, a pair of independently acting lever-receiving socket-members 110 pivotally mounted upon said pivotal support, adapted to receive an actuating lever, and independent means, connected with each socket-member for independently operating 115

120

1. A combination jack and hoist, comprising a chambered standard, a jack-mechanism and a hoist-mechanism disposed in said standard, a means of pivotal support within said standard, a pair of independently acting lever-receiving socket-members 125 pivotally mounted upon said pivotal support, adapted to receive an actuating lever, and independent means, connected with each socket-member for independently operating 130

- the jack-mechanism or the hoist-mechanism according to the actuated socket-member.
2. A combination jack and hoist, comprising a chambered standard, a rack vertically movable in said standard, a chain-carrier rotatably disposed within said standard, a means of pivotal support also disposed within said standard, a pair of independently acting lever-receiving socket-members pivotally mounted upon said pivotal support, adapted to receive an actuating lever, means connected with one of said socket-members for operating said rack, and means co-operating with the other socket-member and the said chain-carrier for actuating said carrier. 65
3. A combination jack and hoist, comprising a chambered standard, a rack vertically movable in said standard, a chain-carrier rotatably disposed within said standard, a means of pivotal support also disposed within said standard, a pair of independently acting lever-receiving socket-members pivotally mounted upon said pivotal support, adapted to receive an actuating lever, a pair of spring-controlled and pivoted pawls co-operating with one of said socket-members for operating said rack, and means co-operating with the other socket-member and the said chain-carrier for actuating said carrier. 70
4. A combination jack and hoist, comprising a chambered standard, a rack vertically movable in said standard, a chain-carrier rotatably disposed within said standard, a means of pivotal support also disposed within said standard, a pair of independently acting lever-receiving socket-members pivotally mounted upon said pivotal support, adapted to receive an actuating lever, a pair of spring-controlled and pivoted pawls co-operating with one of said socket-members for operating said rack, a pair of spring-controlled and pivoted pawls co-operating with the other socket-member, a shaft extending across said standard, a ratchet-wheel mounted upon said shaft with which said last-mentioned pawls are adapted to be brought in engagement for actuating said ratchet-wheel and shaft, a pinion also mounted upon said shaft, a second shaft extending across said standard upon which said chain-carrier is mounted, and a gear-wheel mounted upon said last-mentioned shaft in mesh with said pinion for actuating said chain-carrier. 75
5. A combination jack and hoist, comprising a chambered standard, a rack vertically movable in said standard, a chain-carrier rotatably disposed within said standard, a means of pivotal support also disposed within said standard, a pair of independently acting lever-receiving socket-members pivotally mounted upon said pivotal support, adapted to receive an actuating lever, means connected with one of said socket-members for operating said rack, a pair of spring-controlled and pivoted pawls co-operating with the other socket-member, a shaft extending across said standard, a ratchet-wheel mounted upon said shaft with which said last-mentioned pawls are adapted to be brought in engagement for actuating said ratchet-wheel and shaft, a pinion also mounted upon said shaft, a second shaft extending across said standard upon which said chain-carrier is mounted, and a gear-wheel mounted upon said last-mentioned shaft in mesh with said pinion for actuating said chain-carrier. 80
6. A combination jack and hoist consisting of a base-plate having chain-receiving openings, vertically disposed side-plates mounted upon said base-plate, said side-plates having portions contracted toward each other to provide a rack-receiving space, a spacing plate and a gate-plate mounted between said side-plates, a ratchet wheel-receiving casing mounted upon the outer side of one of said side-plates, and a gear-casing mounted upon the outer side of the other side-plate, a supporting pin extending across the space between said side-plates and extending also into the ratchet-receiving casing, a lever-receiving socket-member oscillatorily mounted upon that portion of the pin between the said side-plates, a second lever-receiving socket-member oscillatorily mounted upon that portion of the pin within said sprocket-wheel receiving casing, a rack vertically movable in the space between the contracted members of the said side-plates, a pair of spring-controlled and pivoted pawls co-operating with said first-mentioned socket-member for operating said rack, a pair of spring-controlled and pivoted pawls co-operating with said second-mentioned socket-member, a shaft extending across the space between said side-plates and at one end into said ratchet-wheel receiving casing and at its other end into said gear-casing, a ratchet-wheel mounted upon the end of said shaft within the ratchet-wheel receiving casing, with which said last-mentioned pawls are adapted to be brought in engagement for actuating said ratchet-wheel and shaft, a pinion mounted upon the other end of said shaft within said gear-casing, a second shaft extending across the space between said side-plates and at one end into said gear-casing, a chain-carrier mounted upon said last-mentioned shaft between said side-plates, and a gear-wheel mounted upon the end of said last-mentioned shaft within the gear-casing with which said pinion is in mesh for actuating said last-mentioned shaft and the chain-carrier. 85
7. A combination jack and hoist, comprising a chambered standard, consisting of a base-plate having chain-receiving openings, vertically disposed side-plates, a spacing- 90

- 125

plate, and a gate-plate, a jack-mechanism and a hoist-mechanism within said standard, means for independently operating said jack and hoist-mechanisms, and a chain movably disposed in the openings of said base-plate and co-operating with said hoist-mechanism, but, when the jack-mechanism is being operated, being adapted to be with-drawn from said openings and through the opened portion of the standard when the gate-plate has

been brought into an opened relation to said standard.

In testimony that I claim the invention set forth above I have hereunto set my hand this 3rd day of February, 1922.

THOMAS H. DARDANI.
